(57) CLAIM

The design for the combined pillow case, top cover with dual pockets, as shown and described.

DESCRIPTION

FIG. 1 is a front perspective view of the combined pillow case, top cover with dual pockets showing my new design;

FIG. 2 is a front elevational view of the combined pillow case, top cover with dual pockets thereof;

FIG. 3 is a rear elevational view of the combined pillow case, top cover with dual pockets thereof;

FIG. 4 is a right side elevational view of the combined pillow case, top cover with dual pockets thereof;

FIG. 5 is a left side elevational view of the combined pillow case, top cover with dual pockets thereof;

FIG. 6 is a top plan view of the combined pillow case, top cover with dual pockets thereof; and,

FIG. 7 is a bottom plan view of the combined pillow case, top cover with dual pockets thereof.

In the drawings, the broken lines represent stitching.
